SIDE WALL SEAL FOR FLOATING TANK ROOFS

John H. Wiggins, Chicago, Ill.

Original application December 2, 1938, Serial No. 247,031. Divided and this application January 2, 1941, Serial No. 372,866.

1 Claim. (CL 220—26)

This application is a division of my application Serial No. 247,031, for Floating tank roofs, filed December 2, 1938.

This invention relates to side wall seals for floating tank roofs.

The main object of my present invention is to provide a novel side wall seal that comprises a supporting means, which is of such design or construction that the seal will be mounted on the floating roof in a manner that insures said seal being maintained in approximatively parallel relationship to the tank side wall and permits the parts of said seal that are in rubbing contact with the tank side wall to move freely in all directions in a horizontal plane. Other objects and desirable features of my invention will be hereinafter pointed out.

Figure 1 of the drawing is a top plan view of a floating tank roof provided with a side wall seal constructed in accordance with my invention.

Figure 2 is an enlarged vertical sectional view, taken on the line 2—2 of Figure 1; and

Figure 3 is a vertical sectional view, taken on the line 3—3 of Figure 2, looking in the direction indicated by the arrows.

The side wall seal that constitutes my present invention is provided with a supporting means that comprises a plurality of hangers rockably mounted on the floating roof and disposed so that the upper ends or free ends of said hangers lean against the inner face of the tank side wall, plus a means for suspending said side wall seal, from said hangers in such a manner that said seal hangs substantially like a curtain. Preferably, the means that suspends the side wall seal from the hangers are constructed so that the seal can be adjusted vertically to change the horizontal relationship between the seal and the roof and maintain the seal in correct parallel relationship with the tank side wall. Said hangers are arranged in spaced relationship around the peripheral portion of the floating roof, and are of such design that in addition to suspending the side wall seal in a vertical position, said hangers exert pressure on the floating roof in a manner tending to maintain said floating roof in concentric relationship with the side wall of the tank. This method of mounting a side wall seal on a floating tank roof is desirable, in that it utilizes the tank side wall to furnish one component of the force required to sustain the hangers and the load thereon, and it allows the side wall seal to move freely in all directions in a substantially horizontal plane. In other words,

it is capable of moving inwardly and outwardly relatively to the roof and is capable of a slight circumferential movement. The particular construction of the side wall seal is immaterial, so long as it consists of a circumferentially flexible cylindrical-shaped member or part of substantial height or depth, that bears against the inner side of the tank side wall and extends around the entire circumference of said side wall. I have herein illustrated the side wall seal as consisting of a circumferentially flexible shoe of substantial height, constructed so as to be capable of conforming, or approximately conforming, to the shape of the curved or circular-shaped side wall of the tank, as described in my parent application, said shoe being constructed in the form of a split ring or made up of a plurality of relatively long arc-shaped members or segmental members.

In the accompanying drawing which illustrates the preferred form of my invention, 1 designates the side wall of the tank, 2 designates the floating roof, and A designates a side wall seal formed by a split ring or shoe extending unbrokenly around the tank side wall and provided with a single gap that is closed or sealed by a vertically-disposed sealing device 100, shown in Figure 1, that may be of any preferred type or kind, so long as it provides for the expansion and contraction of the shoe A. Instead of being constructed in the form of a split ring, the side wall seal A might be composed of a plurality of relatively long arc-shaped or segmental-shaped shoe members whose ends are joined together by flexible connecting devices, as is more or less standard practice. In general form or outline the side wall seal A, as an entirety, resembles a relatively deep, vertically-disposed cylinder arranged in parallel relationship with the tank side wall, but as previously stated, said cylinder may be composed of one substantially continuous member provided with a sealed gap, or a plurality of segmental sections of substantial length with sealed gaps between the ends of same.

The side wall seal or shoe A is supported by a plurality of rockable hangers B arranged on the top side of the roof 2 in spaced relation around the peripheral portion of same. Preferably, each of the hangers B is composed of an upright member formed preferably by a piece of angle iron, whose lower end portion has attached to same a horizontally-disposed trunnion 6 that is supported in bearings 7 on the floating roof. The hangers move freely inwardly and outwardly, but they are effectively held against

sidewise movement. At the upper end of the member B is a bracket 8, from which is suspended a swinging rod 9 provided at its lower end with a hook 10 on which the seal A is supported, preferably by the reinforcing member or bar 3 at the top edge of said seal. The rod 9 passes freely through a hole in the bracket 8, and in order that the side wall seal may be adjusted vertically relatively to the hanger, the rod 9 is provided with a screwthreaded portion 9^a that receives either a nut mounted on the top side of the bracket, or a pair of nuts 9^b arranged above and below the bracket 8. By adjusting the rods 9, the level of the side wall seal can be changed so as to maintain said seal in parallel relationship with the side wall of the tank. The swinging hanger B is provided at its upper end with a roller or equivalent anti-friction device 11 that engages the inner face of the side wall 1 of the tank, and a resilient means is associated with said hanger B, so as to normally hold it in a certain approximate position, but permit said hanger to move inwardly and outwardly slightly with relation to the side wall of the tank. Preferably, the means just referred to is formed by a spring rod F arranged vertically in a socket 12 on the floating roof, and provided at its upper end with a connecting member 13 that joins said spring rod F to the hanger B. In the preferred form of my invention herein illustrated the connecting member 13 is formed by a horizontally-disposed rod pivotally connected at 14 to the hanger, and provided at its opposite end with a threaded portion 14^a which carries two nuts 15 that are arranged at the opposite sides of a bracket piece 16 on the upper end of the spring rod F. The rod 9, from which the side wall seal A is suspended, gives a vertical lift in all positions, and causes the lift on the seal to go right against the seal itself, thereby eliminating all overturning movement. In effect, the side wall seal A resembles a relatively deep cylindrical curtain that hangs parallel to the side wall of the tank and which is suspended from an overhead supporting structure formed by the swinging hangers B on the roof. If said curtain-like seal A moves circumferentially relatively to the floating roof, the weight of said curtain-like seal will bring it back to its normal position. The roller 11 at the upper end of the hanger makes the hanger practically frictionless, and on account of the relatively great length of the swing-

ing hanger B, the horizontal thrust of said hanger on the tank wall is very small and this is decreased to nearly zero by the pull back effect of the spring rod F. Thus, all the forces on the hanger relative to the roof tend to center the roof in the tank. In the normal operation of the roof of the spring rod F pulls the hanger back, if it moves out, and pushes the hanger out, if the hanger moves inwardly from the position shown. The horizontal thrust of the side wall seal weight and friction is taken by the roller 11 at the upper end of the hanger, thus eliminating friction, due to side wall seal weight.

Due to the fact that the seal is circumferentially flexible and is suspended like a curtain from an overhead supporting structure carried by the roof, a means must be employed to force the seal outwardly against the side wall of the tank. In the particular structure herein shown the side wall seal A is acted on intermediate its top and bottom edges by presser bars D' that exert an outward pressure on said seal A in such a way as to produce a line contact between the tank side wall and the seal A throughout the entire circumference of said seal. Said presser bars D' can be constructed and arranged in various ways, but they are here shown as being carried by spring-actuated, rockable devices mounted on the roof 2 in such a way that the presser bars D' engage the seal A intermediate the top and bottom edges of same and force said seal outwardly towards the side wall of the tank.

Having thus described my invention, what I claim as new and desire to secure by Letters Patent is:

In a container for storing liquids, the combination of a tank side wall, a floating roof, an annular-shaped side wall seal of substantial height or depth, disposed in approximately parallel relationship with said side wall, hangers on the roof, mounted so as to be capable of rocking inwardly and outwardly towards and away from said side wall, swinging links on said hangers from which said seal is suspended, including means for adjusting said seal vertically relatively to said hangers, so as to change the horizontal relationship between said seal and the roof, and devices that exert outward pressure on the seal intermediate the top and bottom edges of same to force the seal outwardly towards the tank side wall.

JOHN H. WIGGINS.
